INTERNAL-COMBUSTION PUMPING-ENGINE.

1,006,540.

Specification of Letters Patent. Patented Oct. 24, 1911.

Application filed October 10, 1910. Serial No. 586,212.

To all whom it may concern:

Be it known that I, CHARLES EMMONS, a citizen of the United States, residing at Everett, in the county of Snohomish and State 5 of Washington, have invented certain new and useful Improvements in Internal-Combustion Pumping-Engines, of which the following is a specification.

This invention relates to apparatus for 10 pumping water.

The special object of my improvements is to produce a pump in which the water admitted into a pair of drums is alternately exposed to the dynamic force generated by 15 the explosion of combustible gases to expel the same therefrom to effect the pumping operation.

A further object of the invention is to provide 20 a novel form of pump in which the pumping explosions will be regular and the water delivery will not fluctuate to an appreciable extent.

Having the foregoing objects and others 25 of general utility in view, the invention consists in the novel construction and combination of parts, as will be hereinafter described and claimed.

In the accompanying drawings, Figure 1 30 is a view partly in front elevation and partly in transverse section of pumping apparatus embodying my invention. Fig. 2 is a similar view illustrating the pump controlling devices. Fig. 3 is a view from the rear of the device as shown in Figs. 1 and 2 and 35 illustrating the valve employed in directing the combustible gases alternately into the pump drums. Fig. 4 is a sectional view taken through Fig. 2.

In said drawings, the reference numeral 40 5 designates a power-operated compressor for a mixture of explosive gases, such as gasolene, distillate oils, etc., which are introduced to the compressor cylinder 6 through a carbureter which is indicated conventionally at 7 in Fig. 1. Since these 45 instrumentalities may be of any suitable type, the construction thereof need not be described in detail in the specification.

The discharge for the gases compressed in 50 said cylinder is through a pipe 8 which is connected by pipe-branches 9 and 9' with drums 10 and 10'. Positioned at the junction of said pipes is a plug valve 11 which,

as shown in Fig. 3, has a duct 12 leading therethrough and arranged to afford communication between the pipe 8 and either of its branches. It is designed to have said drums submerged in the body of water which is to be pumped. At the bottom of each of the drums is an inlet opening 13 provided with a seat for an upwardly opening valve 14. Discharge openings are provided at or in proximity to the bottoms of the respective drums which are connected by pipes 15 and 15' with the delivery pipe 16. 65 Included in each of the pipes 15 is a check or non-return valve indicated by 17. Adjacent to the top of each drum is a passage 18 leading into the respective chambers 19 and 19'. Said passages are each provided 70 with a valve 20 opening inwardly with respect to the drums and mounted for horizontal movement with stems 21 which operate in guides 22. Provided for each said valve and positioned in the respective chambers is a float 23 which is carried upon one arm of a bell-crank 24 whose other arm 24' is connected with a valve-stem 21 as by extending through a slot in the latter. 75

Supplementary bell-cranks 25 are provided in the respective drums and have one arm 25' of each connected with the valves 20, as by extending through a slot of a stem 21, while the other arms of these bell-cranks are connected with the valves 14 by rods 85 26, thus causing the valves 14 and 20 of each of said drums to open or close only in unison.

27 represents vent pipes extending from the top of the chambers 19 and 19' for the escape of the spent gases produced by the 90 explosions occurring in the drums. 28 represents strainers provided for said drum inlet openings.

The aforesaid valve 11 has secured thereto an operating arm 29 extending 95 upwardly and near its extremity is pivotally connected to the lower end of a rod 30. This rod extends through an aperture in and to a distance beyond a swivel-pin 31 which is socketed in a fixed support 32 100 which, for example, may be secured to the pipe 8 or an attachment thereto. The axis of the pin 31 is disposed to be in the same vertical plane with the axis of the valve 11. Interposed between the valve arm 29 and 105 the pin 31 there is carried by rod 30 a heli-

cal spring 33. Located at opposite sides of the valve arm 29 is a pair of axially aligned cylinders 34 and 34' which communicate from near their outer ends by tubes 35 with the pipes 9 and 9'. A piston 36 is provided for each cylinder and have their rods 37 extend through the inner ends of the respective cylinders. An enlarged head 38 is provided upon the piston rods exteriorly 10 of the respective cylinders and are normally held against the ends of the latter by springs 39 acting against the pistons and within the cylinders.

40 and 40' represent terminals of normally incomplete electric circuits 41 and 41' which include sparking appliances 42 and 42' introduced either in the top ends of the drums 10 and 10', but preferably in the pipes 9 and 9' communicating therewith so 15 as to be located above the height at which the water ascends in the drums. To close said electric circuits there is employed switch elements 43 and 43' desirably formed in the shape of bell-cranks having depending 20 fingers 44 and 44' which are adapted to be swerved by the end of the rod 30 to swing the first encountered one of the switch elements into position to close the circuit gap and in opposition to the springs 45 or 45' 25 which act to retain the switch elements in inoperative positions.

It is to be noted that the drums 10 and 10', being submerged in water, will naturally be filled with the same when the respective in- 30 take valves 14 are open coincidently with the valves 20 to allow the water to enter by the former and the escape of gases from within the drums through the vent pipes 27. In operating the invention, however, 35 the water is admitted alternately in the two drums and when one of them, as 10' for example, is filled or nearly so with water, the chamber 19' is flooded, resulting in the raising of the associated float 23 and 40 the closure of the valves 20 and 14 through the medium of the bell-crank 24. Mean- 45 while the compressor 5 has been operating to compress a charge of the explosive mixture which then flows through the pipe 9' 50 to fill the space above the water level in this drum and likewise flowing through a tube 35 into the cylinder 34' until the pressure therein is sufficient to overcome the power of the spring 39. Whereupon the piston 36 55 is forced toward the other end of this cylinder causing the piston rod 37 to push against the valve arm 29 to swing the same with the rod 30, which is pivotally connected thereto, beyond a vertical plane extend- 60 ing through the axis of the valve 11. After said valve arm and the rod 30 have been 65 swung the spring 33 asserts itself to carry the valve arm and rod into the positions in which they are respectively indicated by broken lines α and β in Fig. 2. When the

rod 30 is thus swung, the finger 44' of the switch element 43 is engaged thereby to swing such switch element into closed position with respect to its electric circuit 41' and afford an ignition spark to explode the 70 charge of combustible previously admitted above the water in drum 10'. When the explosion occurs, a pressure is created upon the water surface to drive the body of water downwardly in the drum 10' and discharge 75 the same through the outflow pipe 15' into the delivery pipe 16. When the water is thus driven from the drum 10' the weight of the water within the compartment 19' opens the valve 20 and then empties into 80 the drum to be replaced by the gaseous combustion products which escape through the vent pipe 27 accelerated by the water which again enters through the inlet 13 of this drum. The ultimate swinging movement of 85 the valve arm 29 having meanwhile affected the valve 11 to close communication between the pipe 8 and the pipe 9' and at the same time afford a delivery of a charge of explosive gases from the compressor through pipe 9 into the drum 10 subsequent to the filling of the drum with a charge of water, and eventually the pressure of the gases will act on the piston in cylinder 34 to actuate the 90 valve-arm 29 for the reversal of valve 11 95 and to swing the rod 30 to effect the explosion of the combustible present above the water in drum 10 to drive the water therefrom through pipes 15 and 16.

It is to be noted that, with the duplex type shown, the explosive impulses with which the water is forced are successive and continuous; also that the number of drums or pairs of drums and their connective and synchronizing mechanism connected to a 100 single discharge pipe or that may be coupled to a single compressor may obviously be varied in accordance with the demand, it being deemed sufficient to the understanding of the invention to illustrate it in the 105 present manner.

What I claim, is—

1. In a pumping apparatus, the combination of a compressor, a drum communicating with the compressor and provided with water inlet and discharge openings, controlling valves for said openings, a chamber communicating with said drum and provided with an outlet for the escape of gases therefrom, a valve for the passage between the 115 drum and said chamber, a float in said chamber operatively connected with the last named valve for closing said passage through the presence of water in the chamber, normally inoperative electric devices 120 for igniting successive charges of explosive mixture introduced into the drum from said compressor, and means operated through the pressure generated by said compressor for 125 periodically interrupting the flow of the 130

combustible mixture into the drum and likewise rendering said igniting devices operative to effect the explosion of charges of said mixture within the drum.

2. In pumping apparatus of the class described, the combination with a power operated compressor, of a pair of drums having water inlet and discharge openings in proximity to their lower ends, controlling valves for said openings, chambers communicating with the respective drums in proximity to the tops of the latter, a vent pipe extending from each of said chambers, valves for closing the passage between the respective chambers and drums and operatively connected with the controlling valves of said water inlet openings, a float positioned in each said chamber, operative connection between the valves of said passages and the floats whereby the flooding of the chambers with water will influence the valves thereof to close such passages, a discharge pipe for the delivery of charges of explosive mixtures from said compressor, branch pipes connecting said discharge pipe with the drums, a reverse valve for regulating the flow of the explosive mixture from said discharge pipe into the branch pipes, an arm actuating the last named valve, a normally incomplete electric circuit for each of said drums and severally provided with ignition devices, a switch element for each of said circuits and arranged to be actuated by the last named rod when the same is swung from one side or the other to effect the explosion of gases admitted into the drums to expel the water therefrom.

3. In pumping apparatus of the class described, the combination with a power operated compressor, of a pair of drums having water inlet and discharge openings in proximity to their lower ends, controlling valves for said openings, chambers communicating with the respective drums in proximity to the tops of the latter, a vent pipe extending from each of said chambers, valves for closing the passage between the respective chambers and drums, a float positioned in each said chamber, operative connection between the valves of said passages and the floats whereby the flooding of the chambers with water will influence the valves thereof to close such passages, a discharge pipe for the delivery of charges of explosive mixtures from said compressor, branch pipes connecting said discharge pipe with the drums, a reverse valve for regulating the flow of the explosive mixture from said discharge pipe into the branch pipes, an arm for actuating the last named valve, a pair of cylinders disposed upon opposite sides of this valve and communicating with the aforesaid branch pipes, a spring pressed piston in each of the cylinders, a rod for each piston, a swivel pin, a rod pivotally

connected with said valve arm and extending through an aperture provided in the pin, a normally incomplete electric circuit for each of said drums and severally provided with ignition devices, and a switch element for each of said circuits.

4. In pumping apparatus of the class described, the combination with a power operated compressor, of a pair of drums having water inlet and discharge openings in proximity to their lower ends, controlling valves for said openings, chambers communicating with the respective drums in proximity to the tops of the latter, a vent pipe extending from each of said chambers, valves for closing the passage between the respective chambers and drums, a float positioned in each said chamber, operative connection between the valves of said passages and the floats whereby the flooding of the chambers with water will influence the valves thereof to close such passages, a discharge pipe for the delivery of charges of explosive mixtures from said compressor, branch pipes connecting said discharge pipe with the drums, a reverse valve for regulating the flow of the explosive mixture from said discharge pipe into the branch pipes, an arm for actuating the last named valve, a normally incomplete electric circuit for each of said drums and severally provided with ignition devices, a switch element for each of said circuits, and means actuated by pressure generated in said compressor for influencing said arm to reverse the reverse valve and likewise serving to operate the switch elements to effect the explosion of gases in drums alternately.

5. In pumping apparatus of the class described, the combination with a power operated compressor, of a pair of drums having water inlet and discharge openings in proximity to their lower ends, controlling valves for said openings, chambers communicating with the respective drums in proximity to the tops of the latter, a vent pipe extending from each of said chambers, valves for closing the passage between the respective chambers and drums and operatively connected with the controlling valves of said water inlet openings, a float positioned in each said chamber, operative connection between the valves of said passages and the floats whereby the flooding of the chambers with water will influence the valves thereof to close such passages, a discharge pipe for the delivery of charges of explosive mixtures from said compressor, branch pipes connecting said discharge pipe with the drums, a reverse valve for regulating the flow of the explosive mixture from said discharge pipe into the branch pipes, an arm for actuating the last named valve, a normally incomplete electric circuit for each of said drums and severally provided with ignition devices, a switch element for each of said circuits,

and means actuated by pressure generated in said compressor for influencing said arm to reverse the reverse valve and likewise serving to operate the switch element to effect the explosion of gases in drums alternately.

6. In pumping apparatus of the class described, the combination with a power operated compressor, of a pair of drums having water inlet and discharge openings in proximity to their lower ends, controlling valves for said openings, chambers communicating with the respective drums in proximity to the tops of the latter, a vent pipe extending from each of said chambers, valves for closing the passage between the respective chambers and drums and operatively connected with the controlling valves of said water inlet openings, a float positioned in each said chamber, operative connection between the valves of said passages and the floats whereby the flooding of the chambers with water will influence the valves thereof to close such passages, a discharge pipe for the delivery of charges of explosive mixtures from said compressor, branch pipes connecting said discharge pipe with the drums, a reverse valve for regulating the flow of the explosive mixture from said discharge pipe into the branch pipes, an arm for actuating the last named valve, a pair of cylinders disposed upon opposite sides of this valve and communicating with the aforesaid branch pipes, a spring pressed piston in each of the cylinders, a rod for each piston, a swivel pin, a rod pivotally connected with said valve arm and extending through an aperture provided in the pin, a normally incomplete electric circuit for each of said drums and severally provided with ignition devices, a switch element for each of said circuits, and arranged to be actuated by the last named rod when the same is swung from one side or the other to effect the explosion of gases admitted into the drum to expel the water therefrom.

7. In pumping apparatus of the class de-

scribed, the combination with a power operated compressor, of a pair of drums having water inlet and discharge openings in proximity to their lower ends, controlling valves for said openings, chambers communicating with the respective drums in proximity to the tops of the latter, a vent pipe extending from each of said chambers, valves for closing the passage between the respective chambers and drums and operatively connected with the controlling valves of said water inlet openings, a float positioned in each said chamber, operative connection between the valves of said passages and the floats whereby the flooding of the chambers with water will influence the valves thereof to close such passages, a discharge pipe for the delivery of charges of explosive mixtures from said compressor, branch pipes connecting said discharge pipe with the drums, a reverse valve for regulating the flow of the explosive mixture from said discharge pipe into the branch pipes, an arm for actuating the last named valve, a pair of cylinders disposed upon opposite sides of this valve and communicating with the aforesaid branch pipes, a spring pressed piston in each of the cylinders, a rod for each piston, a swivel pin, a rod pivotally connected with said valve arm and extending through an aperture provided in the pin, a normally incomplete electric circuit for each of said drums and severally provided with ignition devices, a switch element for each of said circuits, and means actuated by pressure generated in said compressor for influencing said arm to reverse the reverse valve and likewise serving to operate the switch elements to effect the explosion of gases in drums alternately.

Signed at North Yakima this 30th day of September, 1910.

CHARLES EMMONS.
